UNITED STATES PATENT OFFICE.

EDWARD M. HEWLETT, OF SCHENECTADY, NEW YORK, ASSIGNOR TO
GENERAL ELECTRIC COMPANY, A CORPORATION OF NEW YORK.

CIRCUIT-BREAKER.

No. 826,248.

Specification of Letters Patent.

Patented July 17, 1906.

Application filed May 24, 1898. Serial No. 681,598.

To all whom it may concern:

Be it known that I, EDWARD M. HEWLETT, a citizen of the United States, residing at Schenectady, county of Schenectady, State 5 of New York, have invented certain new and useful Improvements in Circuit-Breakers, of which the following is a specification.

My invention relates to circuit-breakers for power-stations or for any other relation 10 in which it is desirable to open a circuit carrying a heavy electric current.

It has for its object, especially, to provide a reliable and cheap apparatus of the "carbon-contact" type, so called, having a certain delicacy of action not hitherto obtained. The device is also so arranged that the handle moves down to set the contacts instead of moving up, as in many of the devices of this class with which I am familiar. 15 This arrangement enables me to set the circuit-breaker high up on the switchboard, so that when the circuit is opened the arc is above all of the apparatus and is not likely to do injury. I also so arrange the handle 20 that it closes the contacts by a toggle device between the handle and a swinging arm carrying the contacts, the range of motion of which diminishes as the contacts are more nearly closed, so that while the movement of 25 the bridging contact is through air the handle moves comparatively slowly and the contact moves rapidly; but after contact is made between the bridge and the terminals the movement of the handle is greater and 30 that of the contact less, so that an increased leverage is obtained, rendering it comparatively 35 easy to close the contacts.

I also provide in the circuit-breaker a sensitive tripping device working upon the 40 "overset" principle. The two parts of the trip form a toggle, the center of which is on one side of the line joining the centers of motion; but when the circuit-breaker is tripped the joint in the toggle is thrown to the other 45 side of the center and the toggle opens readily. These two parts are free to move between limits.

In some forms of circuit-breaker known to me the handle by which the apparatus is 50 managed is separable and is long, so as to furnish the necessary leverage to close the circuit-breaker with certainty. In addition to the complication of this apparatus it is objectionable because it may well happen that

the circuit will again open just as the handle 55 is removed, in which case it is very apt to cause an accident either to the apparatus or to the operator.

The drawings show an embodiment of the 60 invention.

Figure 1 is a front elevation. Fig. 2 is a side elevation, partly broken away; and Fig. 3, a plan of the apparatus inverted.

A is a base of any suitable non-combustible insulating material, such as slate, which 65 is commonly employed for this purpose.

B B' are the circuit-terminals provided with the flexible extensions or brushes b b'. Between these the bridging contact F closes the circuit. Above the terminals B B' are 70 carbon-terminals C C'. Attached to the bridge F are other terminals D D'. The bridge F is inflexible, while D D' are spring-terminals, and they, with the carbon contacts CC', form a shunt to the main circuit. 75 This arrangement is common in circuit-breaking apparatus. The parts are of course so adjusted that the terminals D D' break from the carbon contacts after the bridge F is withdrawn from the main circuit, thus 80 diminishing the arc and rendering it harmless, it being formed between the terminal D and the contact C, for instance, one of which is of copper and the other carbon, the circuit through which has considerably higher 85 resistance than the main circuit. Between the fixed contacts or terminals is a shield E, of insulating material, which prevents the arc from jumping from one contact to the other. The bridge F is carried upon an arm F'. This latter 90 is pivoted at f' and is connected with the handle H by a link H². The handle H has an arm H', and the pivot H³ of the handle with the arm H' and the link H² pivoted to it and to the arm F' at f², form a toggle, maintained in the illustrated position by the latch 95 I' and the pawl h. A spring G, attached to the handle H at h' and to the arm carrying the bridging contact at f, puts the toggle in operation. As is evident from Fig. 2, the relation of the points of attachment of the 100 spring to the arms of the toggle is such that the spring is not put under tension until the final stage of the toggle-closing movement. When the circuit-breaker is being closed and the bridging contact is moving through the air toward the fixed contact, the spring is 105 under very little tension; which increases

- slowly as the hook h' is moving at substantially a right angle to the axis of the spring; but as the handle H is swung downward at the final stage of the toggle-closing movement to bring the contacts into firm engagement the movement of the hooks h' and f in opposite directions in the line of the axis of the spring puts said spring under tension very rapidly.
- 10 The armature I is under the influence of a series coil L , through which current passes from the stud L' to L^2 , then by the conducting-bar L^3 to the terminal B . The latch I' is pivoted to the armature I , and, as before explained, forms a toggle with the pawl h . It will be seen that the engagement of the pawl is slightly to the right of the center joining its pivot and that of the latch. Pins h^2 h^3 limit the play of the pawl. A wearing-plate i is fixed to the latch I' , and the adjusting-screw i' , fixed to the armature, determines the amount of lost motion allowed to the latter, some slight amount being always given, so that the armature may give a slight hammer-blow to readily disengage the latch. As already explained, the latch and pawl are free to move between stops formed by a toe i^2 and the adjusting-screw i' for the latch and for the pawl by the pins h^2 h^3 .
- 20 A bar O is pivoted at o at the base of the series coil. Through this bar passes a rod attached to the spring M , the other end of which is secured to a fixed part of the frame, and the rod has a nut M' on its lower end by which the tension of the spring is adjusted to determine the load at which the circuit will open. The tripping-handle N of the circuit-breaker is secured by a pin O' to this bar. Of course the working parts of the 30 apparatus have a suitable frame P , carrying the different bearings.
- 25 The operation of the device is as follows: When current in the coil increases to a pre-determined amount, depending upon the tension given to the spring M , which tends to hold up the armature I , the latter is attracted, throwing over the latch I' . The pivoting of the pawl h renders this action sensitive, inasmuch as there is practically no 35 static or sliding friction to be overcome. The spring G then throws down the toggle, turning the handle upon its pivot H^3 to a horizontal position and drawing the bridging contact F to the dotted-line position, thus opening the circuit. When the station attendant desires to close the circuit, he 40 draws down the handle to its illustrated position, when the pawl h again engages the latch and holds up armature I .
- 45 What I claim as new, and desire to secure by Letters Patent of the United States, is—
1. A circuit-breaker having fixed terminals, a supporting-base, a bridging contact adapted to cross connect the same mounted 50 on the supporting-base to swing outwardly

from the terminals, a pivoted handle, a toggle connecting the handle with a point above the point of support for the swinging contact and adapted to shift it to and from the base, a latch for the toggle, and a collapsing spring 70 having one end connected to the handle element of the toggle and the other end to the movable contact-arm.

2. A circuit-breaker having fixed terminals, a bridging contact, a toggle for closing 75 the contacts, a spring for opening them and a detent for the toggle, the detent comprising a latch and a loose pawl, forming together a toggle, a series trip-coil having an armature to which one of the latter is pivoted, the other 80 being pivoted on one of the toggle-levers and means for releasing the latch-toggle by the action of the armature.

3. In a circuit-breaker, the combination with a series coil, an armature, circuit-controlling contacts and mechanism for opening and closing them, of a movable detent for the mechanism comprising a latch pivoted to the armature, a pawl pivoted to the circuit-controlling mechanism, and limiting-stops for the pawl and detent whereby they 85 form a releasing-toggle.

4. In a circuit-breaker, the combination with the main-circuit terminals and a bridging contact, a swinging arm carrying said 95 contact, fixed carbon contacts and spring-contacts upon the swinging arm forming with the carbons a shunt to the main circuit, a series coil, an armature for said coil, a swinging handle, a toggle between the arm and the 100 handle, an auxiliary releasing-toggle controlled by the armature of said series coil, and a collapsing spring connected between the swinging arm and the handle.

5. In a circuit-breaker, the combination, 105 with the contacts, of means for latching them into engagement, a releasing-armature and coil controlling the same, a hand-operated rod attached at one end to the armature and at the other to a pivoted bar, a spring having 110 one end fastened to a fixed part of the frame, and an adjusting device connecting its other end with the bar.

6. A circuit-breaker biased to open when closed, comprising coöperating contacts, an 115 actuating-toggle for throwing said contacts into engagement, two disengageable pivoted members forming a locking-toggle therefor, and means for breaking the latter to free the actuating-toggle and allow the breaker to 120 open.

7. A circuit-breaker comprising two horizontally-disposed fixed contacts having opposing contact-faces, a bridging contact movable between said fixed contacts into engagement with said faces, fixed shunt contacts located above said fixed contacts and extending inwardly therefrom and coöperating 125 movable shunt contacts carried by the bridging contact, a swinging support for said 130

bridging contact, and means for actuating said support.

8. A circuit-breaker comprising two horizontally-disposed fixed contacts, a coöperating movable bridging contact, fixed shunt contacts located above said fixed contacts and extending inwardly therefrom and terminating in opposing contact-faces, coöperating movable shunt contacts carried by the bridging contact and movable between said fixed shunt contacts into engagement with said faces, a swinging support for said bridging contact, and means for actuating said support.

15 9. A circuit-breaker comprising a freely movable contact member, an operating-handle, a toggle between the two, a collapsing spring put under tension by the final stage of the toggle-closing movement, and a latch for holding the circuit-breaker closed.

10. A circuit-breaker comprising fixed and movable contact members, an operating-handle, a spring connecting the handle and

the movable member and tending to open the breaker when closed, means for utilizing the movement of the handle to close the breaker and put the spring under strain, and means for tripping the parts to allow the breaker to open.

11. A circuit-breaker comprising fixed and movable contact members, an operating-handle, a collapsible connection between the handle and movable member for transmitting movement from the former to the latter to set the breaker, a collapsible spring connecting the handle and movable member, and means for breaking the connection so as to free the movable member to permit it to open under the influence of the spring.

In witness whereof I have hereunto set my hand this 14th day of May, 1898.
